US00D744818S

(12) **United States Design Patent**
Matsuo et al.

(10) **Patent No.:** US D744,818 S
(45) **Date of Patent:** ** Dec. 8, 2015

(54) **CONNECTOR FOR SPIRAL HANGER**

(71) Applicant: **Hien Electric Industries, LTD.**, Osaka-shi, Osaka (JP)

(72) Inventors: **Kazuhisa Matsuo**, Osaka (JP); **Shinya Takeda**, Osaka (JP)

(73) Assignee: **Hien Electric Industries, LTD.**, Osaka (JP)

(**) Term: **14 Years**

(21) Appl. No.: **29/477,555**

(22) Filed: **Dec. 23, 2013**

(51) **LOC (10) Cl. 08-05**

(52) **U.S. Cl. USPC D8/382**

(57) **CLAIM**

The ornamental design for a connector for spiral hanger, as shown and described.

DESCRIPTION

FIG. 1 is an upper, front and right side perspective view of a connector for a spiral hanger showing my new design;

FIG. 2 is a front elevation view thereof;

FIG. 3 is a top plan view thereof;

FIG. 4 is a bottom plain view of thereof;

FIG. 5 is a right side elevation view thereof;

FIG. 6 is a front elevation view of the connector in a position of use;

FIG. 7 is a rear elevation view of the connector in a position of use;

FIG. 8 is a right side perspective view of the connector in a position of use;

FIG. 9 is a left side perspective view of the connector in a position of use; and

FIG. 10 is a right side elevation view of the connector in a position of use;

FIG. 11 is a left side elevation view of the connector in a position of use;

FIG. 12 is an additional view of the connector in a position of use;

FIG. 13 is an additional view of the connector in a position of use;

FIG. 14 is an additional view of the connector in a position of use; and,

FIG. 15 is an additional view of the connector in a position of use.

Broken lines in the figures illustrate an environmental structure and form no part of the claimed design.

1 Claim, 13 Drawing Sheets
